UNITED STATES PATENT OFFICE.

ELMER A. CLARK, OF CHICAGO, ILLINOIS.

EXTENSIBLE SUPPORTING DEVICE.

No. 909,990.

Specification of Letters Patent. Patented Jan. 19, 1909.

Application filed September 19, 1907. Serial No. 393,619.

To all whom it may concern:

Be it known that I, ELMER A. CLARK, a citizen of the United States, residing at Chicago, in the county of Cook and State 5 of Illinois, have invented certain new and useful Improvements in Extensible Supporting Devices, of which the following is a specification.

My invention relates to extensible bars or 10 racks and especially to devices of this class which are designed to be slidably retracted into a small compass when not in use, and to receive a number of garment hangers or other devices suspended therefrom.

15 The chief objects of my invention are to provide an extensible device which, when attached to a suitable support, can be wholly or partially elongated and retracted according to requirements.

20 Further objects are to provide an extensible device which will present a strong resistance to deflection, and thus prevent the sagging to which such devices are prone; to produce a contrivance for the purpose stated 25 that when retracted will present a neat appearance; to supply rotatable bearings for the movable parts in order to reduce the friction to a minimum, and to construct the various members of such shape and materials as will prevent warping and sticking of the superimposed parts.

30 I accomplish the above, and other minor results by means of the appliance, illustrated in the accompanying drawing which forms 35 a part of this application, and in which:—

Figure 1 is a side elevation partly in section of my improved rack in retracted position; Fig. 2 is a side elevation, reduced showing the rack extended; Fig. 3 is a perspective view of one of the parting strips or fillers; Fig. 4 is a transverse section; Fig. 5 is a side elevation partly in section of a modified form of the lower casing member; Fig. 6 is a longitudinal section showing a 40 portion of the modified form of the median member or beam, and part of the lower member with one of the parting strips; Fig. 7 is a transverse section of the modified form of rack; Fig. 8 is an end view of a modified 45 form of beam, and Fig. 9 is an end view of the upper casing in the modified form.

50 Referring more in detail to Figs. 1 to 4 of the drawing, the numeral 10 indicates a cylindrical handle having a vertical extension or bracket 11 from the side of which projects horizontally an arm 12 to support

one end of a rectangular hollow casing member 13. The other end of said casing member is connected with the outer extremity of a hollow rod 14 by an angled bracket 15, the 60 end of the said bracket being bent inwardly at 16 to overlap and secure the end of the casing member 13, the extremity of the bracket being bent upward again to form a stop for the purpose hereinafter set forth. 65 The ends of the rods engage lugs projecting from the brackets 15 and 11 and is secured thereto by rivets 17. The upper side of the lower casing member 13 is provided with a longitudinal slot 18, and above said member 70 13 is placed an upper rectangular casing member 19, having a similar slot 18 in the under side. These members 13 and 19 are held together by a median member in the form of an I-beam 25. The web of the beam 75 is located in the slots 18, and the flanges 24 are received with a loose fit in the upper and lower casing members 19, 13. The flanges 24 are supported midway between the top and bottom plates of the casing members by parting strips or fillers 20, 21, said strips having a sliding movement in the members in which they are arranged. The parts thus described have a sliding fit so that the upper and lower casing members 19 and 13 80 85 can be slid upon the I-beam, or the upper casing and beam can be slid upon the lower member. In order to lessen the friction, I furnish the parting strips 20 with rollers 22, mounted upon axles 23, said rollers being 90 housed in slots 22. In order to prevent dislodgment of the sliding parts and to limit the movements of the fillers 20, I provide stops 26 which are secured to the walls of the casing members as shown in said Figs. 1 to 95 4 and project into the path of said strips.

The strips 20 are preferably made of hard wood and may have as many balls or rollers mounted therein as may be desired, their function being to serve as guides and anti-frictional bearings for the slidable members. As shown in Figs. 4 and 7, these bearings are arranged on upper and lower sides of the flanged portions of the slidable bars so that they receive the upward thrust as well as 100 the downward pressure of said bars. The strips being relatively long serve as guides in keeping the bars in true alinement thus avoiding twisting resulting where no such provision is made.

105 It will thus be observed that the hollow quadrangular casing members in connection

with the I-beam upon which they slide form a structure especially adapted to resist vertical stress and the lower member with its brackets and tube is well adapted to support 5 the other extensible parts with the added weight of the articles which may be placed thereon.

Figs. 5 to 9 inclusive illustrate a form of construction slightly modified in the following details. The handle 10^a has an opening 10^b and the stops 26^a are formed by slotting and bending portions of the casing walls 13^a and 19^a. The rollers are replaced by balls 28 which are retained in openings 27 extending through the parting strips 20. The I-beam is constructed of two duplicate channel pieces 30 placed back to back and secured by rivets 31 the margins of the channels thus forming the flanges 29 and resting 20 on or bearing against the rollers or balls. The operation of the structure is the same as described in reference to Figs. 1 to 4.

What I claim is:—

1. In an extensible rack, comprising two 25 or more members slidably arranged relative to each other, anti-frictional means arranged between said members and consisting of a bar having openings therein and rollers mounted in said openings, the faces of said 30 rollers projecting above and below the face of the bar.

2. In a rack, a flanged member, an upper hollow member and a lower hollow member, said members having a sliding relation to 35 each other, and anti-frictional means arranged between said members and comprising a movable bearing strip and anti-frictional devices mounted on said strip.

3. In a rack, a fixed member, a flanged 40 member having a slidable relation to said fixed member, and anti-frictional means arranged between said members, said means comprising a slidable wood strip having openings therein and anti-frictional devices 45 mounted in said openings.

4. In a rack, a fixed member, a flanged

member having a slidable relation to said fixed member, and a bearing strip slidably arranged relative to said members, having anti-frictional means mounted therein. 50

5. In a rack, a fixed member, a flanged member having a slidable relation to said fixed member, a bearing strip having a slid- 55 able relation to said members and a hanger-bar slidably supported on said flanged mem- ber.

6. In a rack, an upper hollow member, a lower hollow member, a flanged bar connect- 60 ing said hollow members, and slidable anti- frictional means arranged between said flanged bar, and each of said hollow mem- bers.

7. In an extensible rack, anti-frictional bearing means comprising a slidabé strip having openings therein and anti-frictional 65 devices mounted in said openings.

8. In an extensible rack, anti-frictional bearing means comprising a slidabé wood strip having openings therein, and rollers mounted in said openings. 70

9. In an extensible rack, a fixed hollow member, a slidabé hollow member, a hanger-rod and a handle secured to said slidabé member, a flanged member connecting said hollow members, and anti-frictional means 75 arranged between the flanges of the flanged member and the opposite walls of the hollow members, said means comprising a slidabé bar and rollers mounted in said bar.

10. In an extensible rack, a fixed hollow 80 member, a slidabé hollow member, a third member connecting said hollow member and slidabé therein, filler strips arranged be- 85 tween the opposed faces of said members, and anti-frictional means mounted in said strips.

In testimony whereof I affix my signature in the presence of two witnesses.

ELMER A. CLARK.
